UNITED STATES PATENT OFFICE.

LOUIS WELLHOUSE, OF ATLANTA, GEORGIA, ASSIGNOR TO ATLANTA BOX FACTORY, OF ATLANTA, GEORGIA, A CORPORATION OF GEORGIA.

PAPER BOX.

SPECIFICATION forming part of Letters Patent No. 687,708, dated November 26, 1901.

Application filed December 22, 1900. Serial No. 40,783. (No model.)

To all whom it may concern:

Be it known that I, LOUIS WELLHOUSE, a citizen of the United States, residing at Atlanta, in the county of Fulton and State of Georgia, have invented certain new and useful Improvements in Paper Boxes; and I do hereby declare the following to be a full, clear, and exact description of the invention, such as will enable others skilled in the art to which it appertains to make and use the same.

This invention relates to boxes in general, and more particularly to paper boxes used for bonbons and similar commodities, the object of the invention being to provide a box wherein the entire exterior, including the bottom, top, sides, and ends, will be covered with ornamental paper, whether figured or plain.

A further object of the invention is to provide a construction wherein the covering of paper will be so secured in place as to give a graceful appearance to the box, said covering being attached only at the free edges of the box.

Additional objects and advantages of the invention will be evident from the following description.

In the drawings forming a portion of this specification, and in which like numerals of reference indicate similar parts in the several views, Figure 1 is a perspective view showing the complete box in closed position. Fig. 2 is a perspective view of the cover of the box with the paper covering thereof unfolded from one end. Fig. 3 is a bottom perspective of the body of the box and showing the paper covering unfolded from one end portion thereof. Fig. 4 is a transverse section through the body of the box. Fig. 5 is a plan view showing the blank from which the covering of the body or the top is made.

Referring now to the drawings, the present box comprises a body portion including a bottom 5, sides 6 and 7, and ends 8 and 9, these portions being of the usual pasteboard and the said body being rectangular in shape. The cover of the box is similar to the body portion and comprises a top 10, sides 11 and 12, and ends 13 and 14 and is a duplicate of the lower portion of the body. The body and the cover when brought together to close the box lie with their sides and ends flush, the

body portion having a lining, including supplemental side pieces 15 and 16 and supplemental end pieces 17 and 18, pasted to the inner faces of the corresponding portions of the lower part of the body, these supplemental walls being put into place after the paper covering is applied, and over the free edges of these supplemental walls the cover is applied.

The covering-blanks for the lower portion of the body and for the cover of the box are the same in shape, material, and size. Each blank consists of a body portion 20, in each end of which are cut two V-shaped or tapered notches 21 and 22, one side of each notch being parallel with the sides of the blank, while the other sides of the notches, which are the outer sides, are at acute angles to the sides of the blank, and the separation of corresponding notches at opposite ends of the blank is equal to the length of the box.

In the application of the blank, say, to the body of the box the body is placed upon the blank and has the inner faces of its sides and ends, at the edges thereof, coated with paste. The sides of the blank are then bent upwardly and over the sides of the body and pasted to the inner face thereof, the tabs between the notches and the side edges of the blank being then bent against the ends of the body, with the upper edges thereof farthest from the notches projecting slightly above the ends of the box and with the lower slanting edges diverging from the bottom of the body. These upwardly-projecting portions are bent over the edges of the ends of the body and pasted in place. The end portions 23 and 24 of the blank between the notches are then bent up against the ends of the body and down over the upper edges of the ends and are pasted against the inner faces thereof. The covering is thus pasted only against the inner faces of the sides and ends of the body of the box, and it is permitted to fit the exterior of the body more or less loosely to give a padded and graceful appearance. The cover of the box is covered with a paper covering in the same manner as is the body and need not be specifically described. The supplemental side and end walls above referred to are pasted against the inner faces of the sides and ends

of the body and against the inturned edges of the covering, as shown. The box is thus provided with a covering on all sides, the covering being so applied as to permit of rapid and cheap construction, while giving a handsome appearance.

It will be readily understood that in practice various modifications of the specific construction shown may be made and that any suitable materials and proportions may be used for the various parts without departing from the spirit of the invention.

What is claimed is—

A paper box comprising a body portion and a cover portion, the cover portion including a top, sides and ends, and a paper blank having two tapered notches in each of its ends for outer tabs and an inner tab at each end, the sides of the blank being bent upwardly and over the upper edges of the sides of the cover and fastened only against the inner faces thereof and having the outer tabs fold-

ed against the ends of the cover and their upper edges folded over against the inner faces of the ends and fastened only thereagainst, and the intermediate tabs being folded up against the outer faces of the ends and over the upper edges thereof to lie against the first-named tabs, said tabs being pasted only against the inner face of the cover, and the body portion being a duplicate of the cover with supplemental walls forming a lining, pasted against the inner faces of the side and end walls and the portion of the blank folded thereagainst and projecting there- above to receive the cover thereover.

In testimony whereof I hereunto sign my name, in the presence of two subscribing witnesses, on the 17th day of November, 1900.

LOUIS WELLHOUSE.
